UNITED STATES PATENT OFFICE

WILLIAM KOCH AND MACK ROGERS, OF MCKITTRICK, MISSOURI

RAIL BRACE

Application filed June 9, 1932. Serial No. 616,338.

This invention relates to railway appliances and contrivances and has more specific reference to a novel device which may be used either as a track gage or a track brace. 5 When used in the latter sense, the device serves to aid in maintaining the track rails in proper spaced parallelism in order to minimize spreading and to thereby render the track more dependable and efficient. 10 We are aware of the fact that braces of this type are not broadly new in the prior art to which the invention relates. Therefore, we take the position that the primary novelty of the instant case is predicated upon a structurally improved and refined brace possessing a number of properly selected and mechanically co-ordinated details co-operating in forming a complete device which we believe better fulfills the requirements of a brace of 15 this type. 20

Other features and advantages of the invention will become more readily apparent from the following description and drawings.

In the drawings:

25 Figure 1 is a fragmentary top plan view of a track and cross ties with one of the braces in operative position.

Figure 2 is a cross section taken approximately on the plane of the line 2—2 of Figure 1.

30 Figure 3 is a detail view in section and elevation showing one end construction of the device.

Figure 4 is a cross section on the line 4—4 of Figure 1.

35 Figures 5 and 6 are perspective detail views.

Figure 7 is a bottom plan view on an enlarged scale showing the turnbuckle and shield arrangement.

40 Figure 8 is a cross section on the line 8—8 of Figure 7.

Figure 9 is a perspective view of one of the essential parts of the rail clamp unit.

45 Figure 10 is a detail perspective view.

In the drawings in Figure 1, the numerals 11 designate ordinary track rails, and the numerals 13 indicate cross ties to which the rails are spiked as are usual.

50 The improved brace, as a whole, is denoted

by the numeral 14. It comprises a pair of duplicate rail clamping units, each unit being the same in construction, and a description of one will suffice for all. Proceeding with this thought in mind, each unit comprises an elongated bar 15 of the type shown in Figure 9 having an integral hook 16 at one end to engage over the base flange of the rail. The opposite end portion of the bar is provided with a reduced screw-threaded shank 55 17.

The intermediate portion of the bar is provided with longitudinally spaced passages or holes 18 and 19. Mounted on each bar is a sliding block-like clamping element 20 having notches 21 formed therein to define a hook 22 to engage over the inner base flange of the rail. As seen in Figure 2, the inner face of said block is recessed to provide a keeper 60 seat 23 as seen in Figure 3.

The keeper is denoted by the numeral 24 and comprises a wire bail having an upstanding U-shaped portion 25 which embraces the rod and is seated in the keeper seat 23. The numerals 26 designate arms terminating in coiled eyes 27 adapted to be selectively registered with the holes 18. A cotter pin or equivalent fastener 28 is passed through the holes 18 and the eyes 27 to hold the keeper 65 70 75 80 24 adjustably in place.

A similar cotter key or pin 29 is passed through the holes 19 and extends across the arms 26 to hold the keeper down in its retaining position.

As seen in Figure 7, the numeral 30 designates a turn buckle which is placed to join the complementary screw-threaded shanks 17 of the respective units together, thus serving to draw the hooks 16 firmly against the base flange of the adjacent rail. Then the slide blocks 20 are slid up against the inner base flanges and fastened in place by the bail-like keepers 24.

The numeral 31 designates a guard or shield which is hingedly attached as at 32 to one of the units and is adapted to swing down over the turnbuckle construction to serve as a shield. This shield carries a resilient clip 33 of the type illustrated in Figure 8 which 85 90 95 100 is engageable between the side members of

the turn buckle as seen in Figure 7 to prevent the turnbuckle from rotating. Thus the shield serves as a protector as well as a retainer for the turnbuckle construction.

5 The numerals 34 designate stay links which are arranged in pairs and pivotally bolted as at 35 to the companion rail clamping units. The outer ends of these links are bolted or otherwise fastened as at 36 to the adjacent cross ties 13 thereby effectively sustaining the brace in position.

10 The gist of the invention is in the provision of a pair of duplicate companion rail clamping units arranged in longitudinal alinement 15 with each other and having their inner ends joined together adjustably through the medium of a turnbuckle, the outer end of said units being formed with rigid hooks to engage over the outer flanges of the rails, said hooks co-20 operating with the slideable hooked block members arranged to engage the inner flanges of the rails.

15 The slideable hooks are such in construction as to be satisfactorily held in place by the 25 U-shaped keepers 24 mounted on the rod portions of the respective units. Each unit is provided with a pair of stay links pivotally connected together at their inner ends and rigidly fastened at their outer ends to the adjacent portions of the cross ties. The turn 30 buckle is equipped with a channel-shaped guard or shield which is swung down to bridge the inner end portions of the units and to cover the turnbuckle construction. In 35 fact, the guard carries a resilient clip which is engageable with the turnbuckle to prevent rotation thereof after it is once set in adjusted position.

40 It is submitted that a structure of this type is desirable as an effective rail brace to prevent spreading of rails and consequent accidents and is also usable as an effective gage to set the rails on the ties at the time of original installation.

45 It is thought that the description taken in connection with the drawings will permit a clear understanding of the invention to be had. Therefore, a more lengthy description is thought unnecessary. While the preferred 50 embodiment of the invention has been shown and described, it is to be understood that minor changes coming within the field of invention claimed may be resorted to if desired.

We claim:

55 1. In a structure of the class described, in combination, a pair of spaced parallel track rails, cross ties located beneath said rails, the rails being fastened to said cross ties in the usual way; a brace located between adjacent 60 cross ties, said brace comprising a pair of adjustably connected clamping units, the outer ends of said units being constructed for releasable engagement with the rails, longitudinally spaced pairs of stay links pivotally 65 connected together at their inner ends to the

respective units and having their outer ends fastened to the adjacent cross ties.

2. A device of the class described comprising a pair of substantially duplicate companion clamping units, each unit comprising an elongated bar having a screw-threaded shank at its inner end and an integral rail flange engaging hook at its outer end, a sliding clamping member on each bar movable toward and from said integral hook, said 70 clamping member being formed with a hook to engage over the adjacent inner flange of the rail, a substantially U-shaped keeper pivotally mounted on each bar and adapted to swing down into abutting relationship with 80 the complementary sliding clamp member, means for holding said keeper in place, a turnbuckle for coupling the screw-threaded shank portions of said units together, a channel-shaped shield pivotally connected to one 85 of said units and swingable over the screw-threaded shanks and turnbuckle, and a resilient clip carried by said shield and engageable with the turnbuckle to prevent rotation 90 of said turnbuckle.

3. A device of the class described comprising a pair of substantially duplicate companion clamping units, each unit comprising an elongated bar having a screw-threaded shank at its inner end and an integral flange 95 engaging hook at its outer end, a sliding clamping member on each bar movable toward and from said integral hook, said member being formed with a hook to engage over the inner flange of the rail, a substantially U- 100 shaped keeper pivotally mounted on each bar and adapted to swing down into abutting relationship with the adjacent sliding clamping member, means for holding said keeper in place, a turnbuckle for coupling the screw-threaded shank portions 105 of the respective units together, and a channel-shaped shield pivotally connected to one of said units and swingable over the complementary screw-threaded shanks and turnbuckle, and a resilient clip carried by said shield and engageable with the turnbuckle to prevent rotation of said turnbuckle, together with pairs of complementary stay links pivotally connected at their inner ends 110 to the units and adapted to have their outer ends fastened to adjacent portions of cross ties.

4. A device of the class described comprising a pair of longitudinally alined companion 120 clamping units, each unit comprising a bar having a rigid rail engaging hook at its outer end, a slideable block-like hook on said bar co-operable with said rigid hook, the inner ends of said units being formed with 125 screw-threaded shanks, a turnbuckle coupling said shanks together, each slideable hook being recessed to form a keeper seat, a keeper comprising a U-shaped wire bail having its arm portions pivotally mounted on said bar 130

and its swingable end portion engageable in said seat, and means for adjustably holding the keeper in closed position.

5. A device of the class described comprising a pair of longitudinally aligned companion clamping units, each unit comprising a bar having a rigid rail engaging hook at its outer end, a slideable block-like hook on said bar co-operable with said rigid hook, 10 the inner ends of said units being formed with screw-threaded shanks, a turnbuckle coupling said shanks together, each slideable hook being recessed to form a keeper seat, a keeper comprising a U-shaped wire bail having 15 its arm portions pivotally mounted on said bar and its swingable end portion engageable in said seat, means for adjustably holding the keeper in closed position, a shield pivotally mounted on one of the units and, 20 adapted to swing over the screw-threaded shank and turnbuckle, and a resilient clip carried by said shield and engageable with said turnbuckle to hold it in a set position.

In testimony whereof we affix our signatures.

WILLIAM KOCH.
MACK ROGERS.
